UNITED STATES PATENT OFFICE.

LOUIS A. STAUCH, OF TOLEDO, OHIO.

GAUGE.

Application filed December 6, 1919. Serial No. 343,038.

To all whom it may concern:

Be it known that I, LOUIS A. STAUCH, a citizen of the United States, residing at Toledo, in the county of Lucas and State 5 of Ohio, have invented certain new and useful Improvements in Gauges; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to gauges constructed for definite predetermined measurements, and is designed to enable the operator to immediately determine, by the sense of touch alone, whether the article to which the 20 instrument is applied is of exactly the required gauge or dimension. While the inventive idea involved in my device may find expression in a great variety of forms, I have in this specification, for illustration, 25 described a specimen which is especially adapted for use in the printing industry, in which the frequent measurements of the lengths of types, the thickness of printing blocks, electrotypes and the like, are necessary 30 in order to insure requisite accurate even printing surfaces. This form of gauge is illustrated in the accompanying drawings, in which—

35 Figure 1 is a perspective view of my device with the movable parts in normal position; Fig. 2 a side-elevation of the same, partly in vertical section, showing the indicator-pin, hereinafter referred to, depressed, and Fig. 3 a top plan-view of a portion of 40 my gauge, taken in section on line 3—3 Fig. 2.

Like parts are represented by corresponding numerals throughout the drawings.

In the drawings, 1 is a base from one end 45 of which springs an overhanging arm 2, these two parts consisting of an integral casting, preferably of steel. The top portion of the arm near its extremity, has, as at 3, a smooth flat surface. Through the arm 50 2 near its outer end is a vertical hole 4 in which reciprocates, with a sliding fit, a pin 5. This pin has a smooth level top which, when moved into the same plane with the portion 3, forms therewith a smooth even 55 unbroken surface. At the bottom the pin is stepped in a socket 6 in the bottom hori-

zontal portion of the part 7, and is there secured by means of a cross-pin 8 passing horizontally through the part 7 and through the lower end of the pin.

In the present example, the member 7 consists of three portions, viz, the bottom part 9 which extends backwardly under the end of the arm 2 and which carries the pin 5; an upright part 10 which rests and slides 65 against the end of the arm 2, and a top, forwardly projecting, horizontal extension 11, which serves as a fingerpiece for the depression of the part 7 with its pin 5. In the part 10 is a vertical slot 12 through 70 which passes a screw 13 which enters the end of the arm 2 and which retains and serves as a guide for the part 7.

14 is a flat spring secured at one end to the part 2, as at 15, and at its other end being bifurcated to bestride and engage the pin 5, as at 16. (See Fig. 3). This spring holds the part 7 and the pin 5 normally elevated as illustrated in Fig. 1. The top of the base 1 and the bottom of the piece 7 constitute the gauge members. The length of the pin 5 is such that when the piece 7 is depressed sufficiently to form the desired gap between the base and the piece 7, the top of the pin will exactly coincide with the 85 surface 3 of the arm 2.

Fig. 2, which illustrates my gauge as applied to a printing type, *a*, clearly shows the operation of my device. In this instance the type is a trifle too short and when, by 90 means of the finger-piece 11, the part 7 is depressed to contact with the top of the type, there is found just above the top of the pin 5, a slight depression which may be instantly detected by merely passing a finger 95 along the surface 3. A depression corresponding in depth to the thickness of the finest sheet of tissue paper is thus at once apparent. If the type or other object is over size, the fact is of course as readily established by a simple touch of the finger upon the projecting pin. If the object to be tested is exactly "to gauge", it is at once proved by passing a finger over the now smooth unbroken surface 3—5.

Having described my invention, what I claim and desire to secure by Letters Patent of the United States, is—

1. A device of the described character having two members providing plane surfaces which when brought into the same plane form a smooth unbroken surface, said

respective members having a pair of gauge portions, and means spaced from said surfaces connected to one of the members to bring the gauge portions to approximate a co-planer measuring position, whereby if the object to be measured be too small, one of said surfaces will be above the other and the reverse if too large.

2. In a device of the described character, 10 a pair of relatively movable gauge-members, a pair of members having respectively a smooth plane surface, connecting means between said pair of members whereby the moving of the gauge-members a predetermined distance apart also places said plane surfaces in the same plane to form a smooth unbroken surface, and manually shiftable means operable for bringing the gauge members to gauge disclosing position, 20 whereby if the object to be measured be too small, one of said surfaces will be below the other and the reverse if too large.

3. In a device of the described character, 25 a base, an arm which springs from and which overhangs said base and which has a smooth even surface, a pin mounted for movement relatively to said arm and having a smooth even unbroken surface, and a gauge member mounted for movement relatively to said base and adapted to establish between the arm and pin a predetermined gauge-distance.

4. In a gauge device, a base, an arm which rises from and overhangs said base and has 35 a smooth even surface, a pin mounted for

movement relatively to said arm and having a smooth even unbroken surface, a gauge member mounted for movement relatively to said base and adapted to establish therebetween a predetermined gauge-distance, and yielding means normally acting to resist movement of the gauge member into position, whereby if the object to be measured be too small, one of said surfaces will be above the other and the reverse if too large.

5. A device of the described character, comprising a base, an arm springing from and overhanging the base, the arm having a smooth upper surface, a member slidably secured to the forward end of the arm and which extends backwardly under the arm, having also a portion which extends forwardly to form a finger-piece, a spring which holds said member normally elevated, a pin reciprocable in said arm and carried by said backwardly turned portion and having a smooth upper end adapted to coincide with the smooth upper surface of the arm, the arrangement being such that when the gap between said backwardly turned portion and the top of the base conforms to the required gauge-distance said two smooth surfaces fall in the same plane.

In testimony whereof I affix my signature in presence of two witnesses.

LOUIS A. STAUCH.
